UNITED STATES PATENT OFFICE.

PETER LESCH, OF NEW YORK, N. Y., ASSIGNOR OF ONE-HALF TO EDWARD WALDSTEIN, OF SAME PLACE.

NON-REFILLABLE BOTTLE.

SPECIFICATION forming part of Letters Patent No. 683,778, dated October 1, 1901.

Application filed February 7, 1901. Serial No. 46,377. (No model.)

To all whom it may concern:

Be it known that I, PETER LESCH, a citizen of the United States, and a resident of the city of New York, borough of Manhattan, in 5 the county and State of New York, have invented a new and Improved Non-Refillable Bottle, of which the following is a full, clear, and exact description.

In carrying out my invention I employ a 10 novel arrangement of valve devices and auxiliary parts, together with an improved float in the form of a buoyant bulb whose function it is to close the valve against the inflowing liquor should the bottle be inverted and the 15 air exhausted therefrom in the effort to refill the bottle. Furthermore, I give to the bottle-neck and its closure devices a form to defeat an attempt to dislodge the said closure devices by means of a wire or the like.

20 The invention consists of novel features and parts and combinations of the same, as will be fully described hereinafter and then pointed out in the claims.

Reference is to be had to the accompanying 25 drawings, forming a part of this specification, in which similar characters of reference indicate corresponding parts in all the views.

Figure 1 is a central sectional elevation of 30 a bottle-neck and inclosure embodying my invention. Fig. 2 is a similar section showing the bottle in inverted position, and Figs. 3, 4, and 5 are separate perspective views of different parts which will be hereinafter more particularly described.

35 Formed integrally with the bottle-neck A and the bottle-body A' is a contracted portion B, provided with a beveled seat b, adapted to receive the correspondingly-formed portion c of a valve C. As particularly shown in Fig. 4, the valve C is provided with a rigid upwardly-projecting hollow stem c' and with a pendant formed with grooves c² to permit the outflow of the liquid, the lower end of the pendant being solid and forming an end weight, 40 which tends to return the valve to its seat. In connection with the solid pendant or other weight which may be employed to insure a seating of the valve I provide further means for normally maintaining the valve in closed 45 position, particularly when the bottle is in inverted position. These means consist of a

coiled spring E, inclosed by the stem c', which spring bears at one end against the closed lower end of the hollow stem c' and shuts at the other end against a shoulder e', formed 55 on an independent rod e, the upper end of which is received in a central recess in the lower portion of a guard-cap F. The valve is held to its seat until the force of the spring is overcome by the pressure of the liquid flowing from the partly-inverted bottle.

On the hollow stem c' of the valve C is fitted a buoyant bulb D, having a central tube d sliding on the stem c. This buoyant bulb D will come into action if it be attempted to 60 refill the inverted bottle after exhausting the air, for the inflowing liquid will float the bulb and will thereby raise the valve C to its seat. The bulb is free to slide relatively to the valve, so that the valve cannot be 65 raised from its seat by pouring liquid into the neck when the bottle is in its normal upright position.

The guard-cap F is cylindrical in form, is 70 open at the top and closed at the bottom, and is provided with side openings f', through which the liquid contents of the bottle may flow out of the open top. As clearly shown in Fig. 3, the guard-cap F is furthermore formed with a peripheral groove f², designed 75 to register with a similar groove a in the bottle-neck. In these grooves a number of bow-springs G are engaged, which are sprung into place in an obvious manner when placing the guard-cap F in the neck. The springs 80 engage both grooves and hold the guard-cap 85 in place. The bottle-neck A is formed with an annular recess a', producing an annular shoulder a² adjacent to the outlet-openings f' of the guard-cap F, so that a wire inserted 90 through one of the openings f' will be arrested by the shoulder a². The neck A projects above the guard-cap F a sufficient distance 95 to receive the usual stopper H.

Having thus described my invention, I 95 claim as new and desire to secure by Letters Patent—

1. A means for preventing the refilling of bottles comprising a valve; a stem above the valve, and a float having sliding movement 100 on the stem.
2. In devices for preventing the refilling

of bottles, the combination of a valve having an upwardly-projecting stem, a cap above the stem, a rod intermediate of the stem and cap, and a buoyant float having sliding movement on the stem.

3. In devices for preventing the refilling of bottles, the combination of a bottle having a neck with an integral contracted portion; a valve therein, having an upwardly-projecting stem; a rod telescoping the stem; a cap above the rod; and a buoyant float having sliding movement on the stem.

4. In devices for preventing the refilling of bottles, the combination of a bottle having a neck with a contracted portion; a valve therein having an upwardly-projecting stem; a spring-acted rod telescoping the stem; a cap above the rod; and a buoyant float having sliding movement on the valve-stem.

5. The combination with a bottle having a neck with an integral contracted portion formed with a valve-seat, a valve adapted to the said seat, the valve having a pendent portion and a hollow stem rising from the upper end, a buoyant bulb having a tubular center fitting the valve-stem, a rod guiding the valve-stem, a cap above the rod, and a spring within the valve-stem, the lower end of the spring having a bearing at the base of the valve-stem and abutting at its upper end on the rod.

In testimony whereof I have signed my name to this specification in the presence of two subscribing witnesses.

PETER LESCH.
